FOLDABLE TENT

Alma L. McGanty, Houston, Tex.

Application August 11, 1950, Serial No. 178,874

3 Claims. (Cl. 135—1)

1

This invention relates to tents, and more particularly to small camping or beach tents.

A main object of the invention is to provide a novel and improved tent which is very simple in construction, which is easy to set up, and which is foldable to a very compact size.

A further object of the invention is to provide an improved foldable tent suitable for use as a camping tent or as a beach tent, the tent being very inexpensive to manufacture, being sturdy in construction, being readily set up or folded to collapsed condition, and involving only a few parts.

Further objects and advantages of the invention will become apparent from the following description and claims, and from the accompanying drawings, wherein:

Figure 1 is a perspective view of an improved tent constructed in accordance with the present invention;

Figure 2 is a front elevational view of the frame of the tent of Figure 1;

Figure 3 is a side elevational view of the frame of the tent of Figure 1;

Figure 4 is an enlarged fragmentary detail view showing an upper corner portion of the frame of the tent, illustrating the manner in which a rigid top strut is secured to the top end of one of the upstanding frame elements;

Figure 5 is an enlarged fragmentary detail view showing the same structure as Figure 4 in front elevation;

Figure 6 is an enlarged fragmentary detail view showing the hinge connection between the lower portion of one of the upstanding frame elements and one of the horizontal foldable strut elements employed in the frame of the tent of Figure 1;

Figure 7 is a cross-sectional detail view taken on line 7—7 of Figure 6;

Figure 8 is an enlarged elevational view showing the hinged connection at the intermediate portion of one of the horizontal strut elements employed in the frame of the tent of Figure 1;

Figure 9 is a top plan view of the structure of Figure 8.

Referring to the drawings, the tent is designated generally at 11. The tent comprises a collapsible frame, indicated generally at 12, over which is secured a flexible covering, such as canvas or other durable fabric, indicated at 13. The frame 12 is generally pyramidal in shape and the cover 13 is formed to closely fit over the frame. At its lower corner portions, the cover 13 is formed with openings 14 adapted to be engaged over downwardly facing hooks 15 secured

in the upstanding frame elements of the tent, whereby the cover is anchored on the frame. The cover is provided in one panel thereof with a conventional zipper, indicated at 16, extending a substantial distance upwardly along the median line of said panel, whereby a passageway into and out of the tent may be provided.

The frame 12 comprises a pair of front upstanding legs 17 and 18, and a similar pair of rear upstanding legs 19 and 20. The respective upstanding legs 17, 18, 19 and 20 are hinged at their mid-portions, the legs 17 and 19 being hinged at their mid-portions, as shown at 21, so that the legs 17 and 19 may be folded in the plane of the panel defined by said legs, and the legs 18 and 20 being hinged at their mid-portions, as designated at 22, the hinges at 22 being arranged so that the legs 18 and 20 may be folded in the plane of the panel defined by said legs, as will be apparent from Figure 1. The lower portions of the legs 17 and 18 are connected by a horizontal strut member 23 which is hinged at its mid-portion, as shown at 24. The ends of the strut member 23 are hinged respectively at 25 and 26 to the respective legs 18 and 17. As shown in Figures 6 and 7, the ends of the horizontal strut 23 may be connected to the upstanding legs by opposing pairs of L-shaped brackets 27, 27 secured to said ends, the upstanding legs being secured between the upstanding elements of the brackets by the respective pivot bolts or rivets 25 and 26. The lower ends of the legs 19 and 20 on the opposing panel of the frame are connected in a similar manner by a horizontal strut element 23' hinged at its mid-portion, as shown at 24', and pivotally connected at its ends to the lower portions of the legs 19 and 20. The upper portions of the upstanding legs 17 and 18 and 19, 20 are connected respectively by short, horizontal strut members 28 and 28', said horizontal strut members being hinged at their mid-portions, as shown at 29, 29', and the ends of said horizontal strut members being hinged to the upper end portions of the respective strut members 17, 18 and 19, 20 in the same manner as the lower horizontal strut members 23 and 23'.

Designated at 30 and 31 are respective arched, rigid strut members removably secured to the top ends of the respective pairs of leg members 17, 19 and 18, 20. As shown in Figures 4 and 5, the ends of the arched, rigid strut members are reduced in thickness, as shown at 32, and the top ends of the upstanding leg members are similarly reduced in thickness, as shown at 33, whereby the ends of the arched strut members

may be overlapped with the top ends of the up-standing legs in the manner shown in Figures 4 and 5. The overlapping ends are secured together by transverse bolts 34 provided with the wing nuts 35.

Referring to Figures 8 and 9, it will be seen that the various hinges employed on the foldable legs 17, 18, 19 and 20 and on the foldable studs 23, 23' and 28, 28' are similar in construction and are arranged so that folding can occur only on one side of the hinge. Thus, in Figure 8, the segments on the opposite sides of the hinge pin 24, designated respectively at 33 and 34, can only be folded downwardly with respect to the hinge pin 24. From Figure 3 it will be seen that the upper segments of the legs 17 and 19 may be folded downwardly and inwardly around the respective hinge pins 21, 21 when the top, rigid, arched connecting strut 30 is removed. Similarly, the upper segments of the legs 18 and 20 can be folded downwardly and inwardly when the rigid top strut 31 is removed. The horizontal struts 23 and 28 on the front side of the frame can be folded upwardly and the horizontal struts 23' and 28' on the opposite or rear side of the frame can be folded upwardly in the same manner. Therefore, to collapse the tent, the cover 13 is first removed, the rigid top struts 30 and 31 are next removed, and the horizontal struts 23, 28, 23' and 28' are then folded upwardly to bring the legs 18 and 17 adjacent each other and the legs 20 and 19 adjacent each other. The upper segments of the legs 18 and 17 are then folded downwardly and inwardly and the upper segments of the legs 19 and 20 are then folded downwardly and inwardly, and then the last pair of horizontal hinged struts shown at 36 and 37 are folded upwardly to complete the folding of the frame. It will be noted that the horizontal strut 36 is pivotally connected at its ends to the lower portions of the legs 17 and 19, and is hinged at its mid-portion, as shown at 38. Similarly, horizontal strut 37 is pivotally connected at its ends to the legs 18 and 20 and is hinged at its mid-portion, as shown at 39. The hinges 38 and 39 are arranged so that the respective struts 36 and 37 may be folded upwardly, whereby the respective segments of said horizontal struts may be brought into adjacency with the lower segments of the respective upstanding legs. The resultant folded frame is very compact in size and may be easily transported or stored.

The reverse procedure is employed to set up the tent. First, the frame is unfolded to the positions shown in Figures 2 and 3, the frame being rigidly secured by connecting the rigid struts 31 and 30 to the top ends of the respective pairs of legs 18, 20 and 17, 19. The flexible cover 13 is then placed over the frame and the openings 14 in the lower marginal corner portions of the cover are engaged over the hooks 15 carried by the legs of the frame.

It will be readily apparent that the tent may be rapidly set up and may be readily handled by a single person. It will also be noted that no tools are required to either set up the tent or to dismantle the tent. When the arched strut members 30 and 31 are fastened to the top ends of the upstanding legs, the frame is rigidly secured and will resist strong winds without collapsing.

While a specific embodiment of an improved foldable tent has been disclosed in the foregoing description, it will be understood that various modifications within the spirit of the invention

may occur to those skilled in the art. Therefore, it is intended that no limitations be placed on the invention except as defined by the scope of the appended claims.

5 What is claimed is:

1. In a tent of the character described, a frame comprising four upwardly convergent foldable post elements, said post elements being hinged at their mid-portion and defining top and bottom segments foldable to side-by-side positions, respective foldable struts connecting the lower portions of said post elements, said struts being also hinged at their mid-portions and being foldable upwardly against the post elements, respective additional foldable struts connecting the upper portions of the post elements on two opposite sides of the frame, said last-named struts being also hinged at their mid-portions and being foldable downwardly against the post elements, and respective rigid struts detachably secured to the upper portions of the post elements on the other two sides of the frame.

2. In a tent of the character described, a frame comprising four upwardly convergent foldable post elements, said post elements being hinged at their mid-portions and defining top and bottom segments foldable to side-by-side positions, respective foldable struts connecting the lower portions of said post elements, said struts being also hinged at their mid-portions and being foldable upwardly against the post elements, respective additional foldable struts connecting the upper portions of the post elements on two opposite sides of the frame, said last-named struts being also hinged at their mid-portions and being foldable downwardly against the post elements, and respective rigid struts detachably secured to the upper portions of the post elements on the other two sides of the frame, said post elements being arranged for folding in the planes of said other two sides.

3. In a tent of the character described, a frame comprising four upwardly convergent foldable post elements, said post elements being hinged at their mid-portions and defining top and bottom segments foldable to side-by-side positions, respective foldable struts connecting the lower portions of said post elements, said struts being also hinged at their mid-portions and being foldable upwardly against the post elements, respective additional foldable struts connecting the upper portions of the post elements on two opposite sides of the frame, said last-named struts being also hinged at their mid-portions and being foldable downwardly against the post elements, respective rigid struts detachably secured to the upper portions of the post elements on the other two sides of the frame, said post elements being arranged for folding in the planes of said other two sides, respective outwardly extending projections carried by the lower portions of the post elements, and a flexible cover fitting over said frame, the bottom margin of said cover being formed with apertures receiving said projections, whereby the cover is secured on the frame.
